UNITED STATES PATENT OFFICE.

ALBERT L. SCHWARTZ, OF PHILADELPHIA, PENNSYLVANIA.

CIGAR AND CIGARETTE ASH CATCHER AND HOLDER.

1,189,878.

Specification of Letters Patent.

Patented July 4, 1916.

Application filed April 23, 1915. Serial No. 23,320.

To all whom it may concern:

Be it known that I, ALBERT L. SCHWARTZ, a citizen of the United States, residing in the city and county of Philadelphia, State of Pennsylvania, have invented a new and useful Cigar and Cigarette Ash Catcher and Holder, of which the following is a specification.

My invention consists of a catcher and holder for the ashes of a cigar or cigarette, the same embodying a casing, and a member adapted to support said casing on the cigar or cigarette at the butt end of the latter and admit of the casing being moved toward the cigar or cigarette as the latter shortens in burning or smoking.

It consists also in adapting the casing to receive the ashes and to break the same in passing therethrough, so as to be effectively directed into the portion of the casing in which they are ultimately deposited.

It consists also of means for preventing the return of the ashes from their final deposit chamber into said primary receiving member.

It consists also of details of construction as will be hereinafter described.

Figure 1 represents a longitudinal section of a catcher and holder for the ashes of a cigar embodying my invention, including also a longitudinal section of the cigar to which the device is applied, and to which the invention in the present instance is limited in the description thereof. Fig. 2 represents a perspective view of detached members of the device. Fig. 3 represents an end view of the casing of the device. Fig. 4 represents a perspective view of a detached member. Fig. 5 represents a partial side elevation and partial longitudinal section of detached members of the device. Fig. 6 represents a side elevation of another embodiment of the invention on a reduced scale.

Similar numerals of reference indicate corresponding parts in the figures.

Referring to the drawings, 1 designates an ash catching and holding casing which is adapted to be sustained on the headed pin or stem 2, the latter being insertible in the cigar 3 and so connected with the same, as to sustain said casing at the butt end of the cigar and receive the ashes of the latter which will drop or fall thereinto. The casing 1 is composed of the body 4 whose end toward the cigar is open and the cap 5 which

is adapted to close the outer end of said casing, it being removably fitted to said body so as to discharge the contents of the latter. Within the body 4 is the coil 6 of wire or other suitable material adjacent to which on the end toward the cap is the concave or dishing diaphragm 7 in which is the port 8, forming a communication between the body and cap. Within the cap is the thimble 9 which is firmly secured thereto and has in it an opening to receive the pin or stem 2, thus supporting said cap on the latter, whereby the body 4 is also supported on said pin, it being noticed that the pin or stem is inserted into the cigar at the butt end thereof and so impaled that the casing is sustained by said pin on the cigar, as plainly shown in Fig. 1. The casing is prevented from displacement from the pin or stem 2 in outward direction by means of the head 2^x of the latter abutting against the outer face of the closing cap 5 of the casing.

On the inner end of the thimble 9 is the disk or head 10 which is adjacent to the port 8, and is of such diameter that while ashes may escape from the body of the casing into the cap at the place of deposit and collection thereof, it will prevent the improper return of the ashes from the cap into the body especially when the cigar is lowered.

The coil 6 is secured within the casing by the clips 11, which extend inwardly from the diaphragm 7 toward the open end of the body 4 and engaged with the convolutions of the coil, and said end of the body with which they are clenched as at 12, said end being also inturned radially forming the flange 13 which in a manner acts as a windguard for the butt end of the cigar and prevents escape of the ashes at said end.

As the cigar burns away in smoking, the cigar will be tilted with the tip end down, when the casing slides automatically on the pin toward the butt of the cigar and closes over the ashes thereon. Then the cigar is again tilted with the butt end down, when the casing will slide automatically from the butt and take the ashes therein with it. As the casing at the end of its play strikes the head of the pin, it receives a jar that will shake the ashes and disintegrate the same, whereby they will pass through the spaces or openings between the coil, so that they will be deposited in the cap.

The outer or closing wall of the cap 5 is adapted to form a broad and flat base on

which the casing 1 may be stood, so that the cigar may be held in upright position thereon when removed from the mouth.

In order to retain the pin in position on the cigar and prevent its accidental withdrawal therefrom, the inner end of the same, which is somewhat flattened and pointed as at 14 to admit of its easy penetration into the cigar, has mounted thereon the flaring spurs 15 of the form of a loop which when the pin is pushed into the cigar pass through the filler and occupy a position near the tip end of the cigar, as shown in Fig. 1. As the spurs flare toward the butt end of the cigar, if the pin is improperly drawn out of the cigar toward said butt end, the points of said spurs take hold of the filler and so resist such drawing-out whereby the pin will retain its position on the cigar.

When the cigar is smoked to comparatively full extent, the pin with its spurs may be readily pulled from the stump. When the pin is passed primarily through the thimble 9, the spurs owing to their construction of light material will enter and move freely through the latter carried by the point-portion of the pin, as shown in Fig. 5.

In Fig. 6 I show a modification where the pin or stem is inserted through the wrapper of the cigar into the filler thereof, so as to be sustained in position, without producing different results to those hereinbefore stated.

Having thus described my invention what I claim as new and desire to secure by Letters Patent, is:—

1. In a catcher and holder for the ashes of a cigar, a pin adapted to be stationarily connected with a cigar, and an ash receiver freely mounted on said pin and adapted to slide thereon toward the butt end of the cigar, and be advanced to the burning end of the cigar as the latter shortens in being smoked without disturbing said pin.
2. In a catcher and holder for the ashes of

a cigar, a hollow body, a disintegrator in the latter, a cap on said body adapted to close the outer end thereof, a diaphragm in said body with which said disintegrator is connected, said diaphragm having therein a port forming a communication between the same and said body and means for attaching said body to a cigar.

3. In a catcher and holder for the ashes of a cigar, a casing, a closing and collecting member on the outer end thereof, a device in said casing adapted to separate the ashes from the cigar and disintegrate said ashes and allow them in disintegrated condition to pass therethrough into said collecting member and means for attaching said casing to a cigar.

4. In a catcher and holder for the ashes of a cigar, a casing, a diaphragm therein, the latter being provided with a port, a closing cap on said casing interiorly in communication with the latter through said port, a head in said cap adjacent to said port, and means for attaching said casing to a cigar.

5. In a catcher and holder for the ashes of a cigar, a casing, a thimble therein, and a stem freely entering said thimble and being thereby adapted to support said casing on the cigar and allow it to be moved to the cigar as the latter shortens in being smoked.

6. In a catcher and holder for the ashes of a cigar, a casing, a stem adapted to support said casing and enter a cigar, and a spur mounted on said stem adapted to spread out from said stem and interlock with the interior of the cigar to prevent improper withdrawal of the stem of the cigar and to be folded into said casing to permit its removal through said casing.

ALBERT L. SCHWARTZ.
